UNITED STATES PATENT OFFICE.

MORRIS H. BENNETT, OF WATERBURY, CONNECTICUT, ASSIGNOR TO SCOVILL MANUFACTURING COMPANY, OF WATERBURY, CONNECTICUT, A CORPORATION OF CONNECTICUT.

ELECTRIC FURNACE.

Application filed June 27, 1923. Serial No. 648,164.

To all whom it may concern:

Be it known that I, MORRIS H. BENNETT, a citizen of the United States, residing at Waterbury, county of New Haven, and State of Connecticut, have invented certain new and useful Improvements in Electric Furnaces, fully described and represented in the following specification and the accompanying drawings, forming a part of the same.

This invention relates to improvements in electric furnaces and has for its object to produce a simple, efficient, inexpensive and compact construction for positioning the electrode or electrodes with respect to the charge and to maintain it or them in such proper position during operation.

More specifically, the invention has for its object to provide means, in an electric furnace in which a secondary current is delivered to the charge by the electrode or electrodes, which will utilize the repulsive force developed between the carrying elements for the primary and secondary currents to properly position the electrode or electrodes with respect to the charge and maintain them in such position during operation.

With these and other objects in view, the invention consists in certain parts, improvements and combinations as will be herein-after fully described and then specifically set forth.

The accompanying drawings illustrate a specific embodiment of the invention, in which—

Figure 1 is an elevation, partly in section, illustrating a construction embodying the invention as applied to the control of a single electrode.

Figure 2 is a diagrammatic view illustrating the circuits which may be employed to adapt the invention to a multi-phase furnace, as, for instance, a three-phase furnace.

In the drawings, 1 indicates a furnace of the usual type, and 2 the charge in the furnace, the electrode being indicated at 3.

It is well-known that where two current carriers, in which the currents are in opposite directions, are employed, each lying in the magnetic field of the other, a repulsive force is developed which tends to separate the current carriers. The present invention provides means which utilize this principle to determine in the first instance

the proper position of an electrode or electrodes of an electric furnace with respect to the charge and to thereafter maintain such proper position, thus enabling the electrode or electrodes to deliver current to the charge during operation without undue variations in the delivery rate.

While the current-carriers employed may be varied in form and arrangement, in the specific construction shown, there is employed a transformer, the core of which is marked 4, the primary current coil 5, and the secondary current coil 6. When a transformer is employed for carrying the invention into effect, one of its coils may be made movable, and this movement may, through proper connections, be caused to shift the position of the electrode. In the construction shown, the secondary coil of the transformer which delivers current to the furnace is the movable coil. When a transformer having a movable secondary coil is employed for carrying the invention into effect, the connections by which the movable coil is caused to move the electrode and the circuit connections may be varied and will vary according to the type of furnace in which the invention is employed.

In the specific construction shown, there is a substantially rigid circuit connection 8 extending from the movable coil to the connection nut 9 in which the electrode is mounted. The secondary coil 6 is mounted in a yoke 10, this yoke being connected by tie rods 11 to extensions 12 of the connection nut 9 before referred to, the usual insulating bushings being employed between the rods and the extensions. This construction has the advantage that the movement of the electrode corresponds exactly with the movement of the secondary coil and further enables the rigid connection 8 heretofore referred to to be employed between the secondary coil and the nut. This rigid connection presents certain mechanical advantages and also materially reduces the electrical losses.

If desirable, the movable electrode and the movable parts connected therewith may be counterbalanced. In the particular construction illustrated, counterbalance cables 13 are employed which are connected to the yoke 10, the connection, in the specific construction illustrated being through rods 26, 27 which will be hereafter described. These

cables run over pulleys 14 and are provided with weights 15. The pulleys 14 are mounted in a yoke 16 which is secured by a bolt 17 to the top of the transformer core.

5 The entire construction may be conveniently supported directly on the furnace top, as by a bracket 19 bolted to the under side of the frame 20 which carries the transformer core and the primary coil.

10 It will be understood that when the furnace is charged the electrode is raised, so that the secondary coil is at or near the top of the transformer core. The line current is now turned on the primary coil. The 15 electrode is then allowed to descend until it touches the charge in the furnace, at which time current begins to flow in the secondary coil. When the current starts to flow in the secondary coil, this coil is repelled and moves away from the primary coil. This movement will continue until the force of the repulsive action between the coils is balanced by the weight of the electrode and the parts connecting it with the secondary coil, at which time the 20 electrode will be properly positioned so as to deliver current to the charge at a rate which will effectively melt the charge.

If desired, certain auxiliary devices may 30 be employed to assist in controlling the movement of and in positioning the electrode. While these auxiliary devices when employed may be varied in construction, a pair of cylinders 21, 22 is provided these 35 cylinders being carried on the frame 16 before referred to. The bottoms of the cylinders 21, 22 are in open communication with the air as shown.

The pipe 28 is led from the top of the cylinder 21 and a similar pipe 29 is led from the top of the cylinder 22, these pipes branching from a pipe 23. Pistons 24, 25 work in these cylinders, these pistons being mounted on the rods 26, 27 which, as before described, are secured to the yoke 10. The pipe 23 leads to a valve chamber 30. This valve chamber 30 has an air inlet pipe 31 which is controlled by a valve 32.

In what are regarded as the best constructions embodying the invention, this valve 32 will be electrically operated. As shown, its stem 33 forms the core of a solenoid 34. This solenoid 34 is connected to the secondary coil 6 by a wire 35 and is connected to the charge by a wire 36. With no current on the furnace the valve 32 will be normally held closed by its own weight and by the weight of its stem 33. When, however, the electrode is in its uppermost 55 position and there is current on the furnace, the potential in the coil 6 will cause sufficient current to flow through the solenoid to cause it to open the valve. During the time, therefore, when the electrode is 60 descending, air will be flowing into the cyl-

inders 21, 22, through the inlet pipes 28, 29, but these pipes will be so proportioned that rate of air supply through them is less than that demanded by the downward movement of the pistons. When the electrode touches 70 the charge, the current flowing through the solenoid will be shunted and the valve 32 will close. At this time, therefore, there will be a partial vacuum in the cylinders above the pistons. When for any reason 75 the current in the secondary increases, so that the electrode is delivering too much current to the furnace, the repulsive action between the coils 5 and 6 will increase, thus causing the electrode to move away from 80 the charge. It is desirable that this movement be unimpeded, so that it may take place quickly. The air cylinder arrangement before described facilitates this movement, due to the fact that the air pressure 85 above the pistons is less than the atmospheric pressure below the pistons so that the pistons have a slight tendency to lift the electrode and the parts connected therewith. As soon, however, as the electrode 90 has moved away from the charge, current is reestablished in the circuit in the solenoid and the valve 32 is opened. The pressure above the pistons, therefore, rapidly becomes atmospheric pressure, and the pistons 95 now tend to check the movement of the electrode in an upward direction.

It will be understood that the parts will be so designed that the proper relation exists between the repulsive action developed between the coils 5, 6 and the weight of the electrode and the parts connected therewith, so that, at the time the repulsive action is balanced by the weight, the electrode will be in a proper position to deliver current to the furnace at a proper rate.

While the invention has been so far described in connection with a single electrode, the construction is adapted for use in a furnace having more than one electrode, and particularly in a three-phase furnace. The connections which may be employed when the invention is embodied in a three-phase furnace are indicated in Fig. 2. In this figure, the cores of the transformers are indicated at 40 and the primary coils at 41. These coils are connected to the line through the usual three-phase delta connection. The secondary coils are marked 42, the leads from these coils to the electrodes being indicated at 43. The common connection between the coils is indicated at 44, the electrodes are shown at 45, and the charge in the furnace is indicated at 46. The valve controlling solenoids are indicated at 47. It will be understood that the mechanical devices hereinbefore described as applied to a single electrode will be applied to each of the three electrodes.

The auxiliary controlling mechanism hereinbefore described is particularly advantageous in connection with a three-phase furnace, because the descending movement of each electrode will be stopped as soon as the electrode touches the charge due to the shunting of the valve controlling solenoids. The digging of any electrode into the charge is, therefore, prevented and a more equal division of the current between the electrodes is effected.

Changes and variations may be made in the construction described and illustrated without departing from the invention herein claimed.

What is claimed is:—

1. In an electric furnace, the combination with an electrode, of means for supplying current to the electrode including a movable element, and means for utilizing the movement of said element to control the position of the electrode with respect to the charge.

2. In an electric furnace, the combination with an electrode, of a transformer for supplying current to the electrode, and means for utilizing the transformer to control the position of the electrode with respect to the charge.

3. In an electric furnace, the combination with an electrode, of a transformer for supplying current to the electrode, said transformer having a movable element, and connections between the movable element and the electrode whereby the movement of said movable element controls the position of the electrode with respect to the charge.

4. In an electric furnace, the combination with means for delivering current to the charge in the furnace, of a transformer having a movable element, and means for utilizing the movement of said movable element to control the current delivered to the charge.

5. In an electric furnace, the combination with means including a transformer for delivering current to the charge in the furnace, said transformer having a movable element, of means for utilizing the movement of said element to control the current delivered to the charge.

6. In an electric furnace, the combination with an electrode, of a current-carrier carrying a primary current, a current in which a secondary current is induced by the primary current, and means for utilizing the repulsive force developed between the carriers by the current flow therein to control the position of the electrode with respect to the charge of the furnace.

7. In an electric furnace, the combination with an electrode, of a coil carrying a primary current, a coil in which a secondary current is induced by the primary current, and means for utilizing the repulsive force developed between the coils to control the

position of the electrode with respect to the charge of the furnace.

8. In an electric furnace, the combination with an electrode, of a transformer, and means for utilizing the repulsive force developed between the primary and secondary elements of the transformer to control the position of the electrode with respect to the charge.

9. In an electric furnace, the combination with an electrode, of a transformer having a movable current-carrying element, and connections whereby the variation in position of the movable element controls the position of the electrode with respect to the charge of the furnace.

10. In an electric furnace, the combination with an electrode, of a transformer having a stationary current-carrying element and a movable current-carrying element, and connections whereby the movement of the movable element controls the position of the electrode with respect to the charge.

11. In an electric furnace, the combination with an electrode, of a transformer, one of the current-carrying elements of which is movable, and means for connecting the movable element to the electrode, whereby variations in position of the movable element vary the position of the electrode with respect to the charge.

12. In an electric furnace, the combination with an electrode, of a transformer, and means for utilizing the repulsive force developed between the primary and secondary elements of the transformer for positioning the electrode with respect to the charge, and auxiliary positioning means.

13. In an electric furnace, the combination with an electrode, of a transformer having a movable current-carrying element, connections whereby variation in position of the movable element positions the electrode with respect to the charge, and auxiliary positioning means.

14. In an electric furnace, the combination with an electrode, of a transformer having a stationary current-carrying element and a movable current-carrying element, connections whereby the movement of the movable element positions the electrode with respect to the charge, and auxiliary positioning means.

15. In an electric furnace, the combination with an electrode, of a transformer, one of the current-carrying elements of which is movable, means for connecting the movable element to the electrode, whereby variation in position of the movable element varies the position of the electrode with respect to the charge, and auxiliary positioning means.

16. In an electric furnace, the combination with an electrode, of a transformer a

23
current-carrying element of which is movable, means for supporting the transformer on the furnace, and connections whereby the movable element of the transformer 5 positions the electrode with respect to the charge.

17. In an electric furnace, the combination with an electrode, of a transformer a current-carrying element of which is movable, means for supporting the transformer on the furnace, connections whereby the movable element of the transformer positions the electrode with respect to the charge, and auxiliary positioning means.

18. In a three-phase electric furnace, the combination with the electrodes, of a transformer unit for each electrode, each of said units having a movable current-carrying element, means for supporting the transformer units on the furnace, and connections between each electrode and the movable element of its transformer unit, whereby the movements of the elements position the electrodes.

25 19. In a three-phase electric furnace, the combination with the electrodes, of a transformer unit for each electrode, each of said

units having a movable current-carrying element, means for supporting the transformer units on the furnace, connections 30 between each electrode and the movable element of its transformer unit, whereby the movements of the elements position the electrodes, and auxiliary positioning means.

20. In an electric furnace, the combination with an electrode, of a transformer having a movable current-carrying element, and rigid connections between said element and the electrode, whereby the element and the electrode move together and the electrode is properly positioned with respect to the charge.

21. In an electric furnace, the combination with an electrode, of a transformer having a movable current-carrying element, rigid connections between said element and the electrode, whereby the element and the electrode move together and the electrode is properly positioned with respect to the charge, and auxiliary positioning devices.
